US0D1076804S

(12) **United States Design Patent** (10) **Patent No.:** **US D1,076,804 S**
(45) **Date of Patent:** **** May 27, 2025**

(54) **WIRELESS CHARGER**

(71) Applicant: **Shenzhen Yifeng Intelligent Technology Co., Ltd.**, Shenzhen (CN)

(72) Inventor: **Ning Liu**, Shenzhen (CN)

(73) Assignee: **Shenzhen Yifeng Intelligent Technology Co., Ltd.**, Shenzhen (CN)

(**) Term: **15 Years**

(21) Appl. No.: **29/918,122**

(22) Filed: **Nov. 24, 2023**

(30) **Foreign Application Priority Data**

Jun. 8, 2023 (CN) 202330352888.5

(51) **LOC (15) Cl.** **13-02**

(52) **U.S. Cl.**

USPC **D13/108**

(58) **Field of Classification Search**

USPC D13/103, 107, 108, 118, 119; D14/434, D14/447, 251, 253

CPC H02J 7/0044; H02J 7/0045; H04B 1/3877; H04B 1/3883

See application file for complete search history.

(57) **CLAIM**

The ornamental design for a wireless charger, as shown and described.

DESCRIPTION

FIG. 1 is a front perspective view of a wireless charger, showing my new design;

FIG. 2 is a front view thereof;

FIG. 3 is a rear view thereof;

FIG. 4 is a left side view thereof;

FIG. 5 is a top view thereof;

FIG. 6 is a bottom view thereof; and

FIG. 7 is a rear perspective view of the merged state thereof; and,

FIG. 8 is a front perspective view of the merged state. The broken lines in the drawings illustrate the portions of the wireless charger, which form no part of the claimed design.

1 Claim, 8 Drawing Sheets
